N. S. Nedder & William L. Sanderson, of Troy, N. Y.

Assignors to

North, Chase, & North, of Philadelphia, Pa.

Letters Patent, No. 839, Dated October 7, 1856.

The Schedule referred to in these Letters Patent and making part of the same.

To all whom it may concern,

Be it known that we, N. S. Nedder, and William L. Sanderson, of the City of Troy, County of Rensselaer, and State of New York, have invented a new and original design for stoves, and we do hereby declare that the following is a full and exact description of the same, reference being had to the accompanying drawings, making part of this specification, in which:

Fig. 1, represents a portion of the bottom plate.

Fig. 2, a front plate.

Fig. 3, a side plate.

Fig. 4, a top plate.

Fig. 5, an iron.

Fig. 6, a foot.

Fig. 7, a hearth slide.

What we claim, as our invention, is the design and configuration of the ornamental plates, as herein described, forming an ornamental design for stoves.
